JAMES BARROWS, OF HYDE PARK, MASSACHUSETTS.

Letters Patent No. 87,321, dated March 2, 1869.

IMPROVEMENT IN SPRINKLERS FOR WATERING-POTS.

The Schedule referred to in these Letters Patent and making part of the same.

To all whom it may concern:

Be it known that I, JAMES BARROWS, of Hyde Park, in the county of Norfolk, and State of Massachusetts, have invented certain Improvements in Sprinklers for Watering-Pots, &c., of which the following is a full, clear, and exact description, reference being had to the accompanying drawings, making part of this specification, in which—

Figure 1 is a perspective view of my improvement. Figure 2 is a central section, representing the same in place upon the spout of a watering-pot.

Figure 3, my improvement detached.

The spout of a watering-pot, of the ordinary construction, is provided with a stationary perforated "rose," or nozzle, through which the water passes in jets upon the ground, plant, or other article or place to be sprinkled.

Owing to extraneous matter contained in the water, the perforations become closed, and the water ceases to flow until the obstruction is removed, which operation is tedious, and inconvenient to perform.

To remedy the above-mentioned difficulty is the object of my invention, which consists in a removable perforated cap, either reversible or not, which may be readily screwed, or otherwise secured upon the enlarged end of the spout of the watering-pot, or upon the enlarged end of a short spout, made independently of the spout of the watering-pot, by which construction, when the perforated cap becomes clogged, it is only necessary to remove and clean it, or reverse it, when it may be quickly returned to its place, the water forcing its way through the perforations when the cap is reversed, and readily removing the obstructions previously collected.

To enable others skilled in the art to understand and use my invention, I will proceed to describe the manner in which I have carried it out.

In the said drawings—

A represents a conical tube, to be placed upon the end of the spout of a watering-pot, the diameter of this tube being contracted at *a*, beyond which point it enlarges rapidly to the point *b*, where a slight shoulder is formed on its outer rim, which is provided with a screw-thread, *c*, over which fits a corresponding thread,

c', cut within the interior of a circular band, or flat ring, B, across the middle of the inside of which extends a plate, C, provided with a series of perforations, *d*, through which the water may pass in jets when the conical tube is fitted in place.

The interior of the end of the circular band B, opposite that bearing the screw-thread *c*, is also provided with a similar screw-thread, *e*, in order that when the perforations *d* become clogged by obstructions collecting on the inner face of the plate C, the band may be unscrewed, and its position reversed, when it can be readily returned to its place, the force of the water within the watering-pot being sufficient to instantly wash away the obstruction.

Instead of placing the perforated plate C at or near the centre of the band B, so as to admit of its reversibility, the plate may cover the end of the band, in which case the latter will not be reversible, and may be cleaned by removing and washing away the obstructions; but I prefer the construction first described.

It is evident that the conical tube A may be dispensed with, and my removable and reversible band, B, be applied directly to the enlarged end of the spout of the watering-pot; and it may also be applied to a syringe or sprinkler for clothes, or other purposes, as the feature of its reversibility renders it particularly useful when so employed.

Instead of screwing the band B upon the enlargement of the conical tube A, the screw-threads may be dispensed with, and the parts made to fit snugly over each other, to prevent leakage, without departing from the spirit of my invention:

Claim.

What I claim as my invention, and desire to secure by Letters Patent, is—

The within-described removable and reversible perforated cap for watering-pots, &c., operating substantially as and for the purpose set forth.

JAMES BARROWS.
